UNITED STATES PATENT OFFICE.

MICHAEL BERT CORCORAN, OF HAMILTON, MONTANA.

EXPANSIBLE HEAD FOR PRESSES.

No. 831,265.

Specification of Letters Patent.

Patented Sept. 18, 1906.

Application filed February 11, 1905. Serial No. 245,256.

To all whom it may concern:

Be it known that I, MICHAEL BERT CORCORAN, a citizen of the United States, and a resident of the city of Hamilton, in the county of Ravalli and State of Montana, have invented certain new and useful Improvements in Expansible Heads for Presses; and I do hereby declare that the following is a full, clear, and exact description of the same, reference being had to the accompanying drawings, and to the letters of reference marked thereon, which form a part of this specification.

This invention relates to presses, and is shown more particularly in relation with a hay-press, though obviously capable of use with presses of many kinds.

Heretofore with hay-presses, particularly with the slower-acting presses, such as those operated by horse-power, a relatively small feed-hole is provided in the top of the press in which to insert the hay or the material to be pressed, and usually the feeder tramps the hay into place during the retraction of the piston or plunger. In numerous instances the feeder, miscalculating the speed of movement of the plunger, has been caught by the return movement and seriously mutilated or crippled for life; but heretofore no satisfactory device has been provided to enable the feeder to throw a quantity of hay or other material into the path of the plunger to afford a sufficient load or charge for the press without the necessity of tramping the same into place, as before described.

The object of this invention is to afford a baler having a large feed-chamber adapted to receive a sufficiently large quantity of the material to be pressed loosely therein to provide a suitable charge for each movement of the plunger and obviating the necessity of endangering the feeder.

It is also an object of the invention to provide a plunger-head of novel construction adapted to engage all the material thrown into the feed-aperture, though distributed over a relatively large area and to compress the same into a relatively narrow space occupied by the bale while forming.

The invention consists in the matters hereinafter described, and more fully pointed out and defined in the appended claims.

In the drawings, Figure 1 is a fragmentary side elevation of a press embodying my invention, showing the feed mechanism closed and the plunger at the limit of its compress-

ing movement. Fig. 2 is a top plan view of the same. Fig. 3 is a central vertical longitudinal section of the same, showing the plunger retracted. Fig. 4 is a central horizontal section of the same. Fig. 5 is a section similar to Fig. 3, but illustrates the compressing movement of the plunger. Fig. 6 is a front end elevation of the plunger. Fig. 7 is a fragmentary horizontal section, showing the plunger at the limit of its compressing movement. Fig. 8 is a fragmentary detail of the articulation of the plunger-blade with the connecting-rod. Fig. 9 is an enlarged sectional detail of the compressing-foot and its shaft.

As shown in said drawings, A indicates the rear end or bale-chamber of a press, such as a hay-press.

A' indicates the body of the press in which the plunger reciprocates, and A² the feed-chamber, into which the hay or other material to be pressed is thrown. In the present construction said feed-chamber is shown to be extended laterally on each side of a median line to approximately twice the width of the bale when formed, as shown in Figs. 2, 4, and 7, and the side walls a of the same taper rearwardly and connect with the side walls of the bale-chamber. Each of the side walls a extends upwardly above the feed-chamber, affording extensions a², which at their rear ends are provided with inwardly-tapering portions a³, as shown in Figs. 1, 3, and 5, continuous with the tapered walls a'.

Pivoted on the top of the bale-chamber, on a shaft b, is a presser-foot B, comprising a plate of sheet metal or other suitable material provided on its upper side with boxes b', rigidly bolted thereto, and in which said shaft is keyed, and thereby rigidly connected with said presser-foot. Said presser-foot B is shaped to fit to the inclined walls a' and a³ of the feed-chamber and between the walls a² thereof and is of a length sufficient to approximately cover the rear half of said feed-chamber when in its depressed position. Said plate also extends rearwardly beneath its shaft b and is adapted to engage when closed with the forwardly-projecting top a⁵ of the bale-chamber, as shown in Fig. 5.

Rigidly secured on each end of the shaft b is a rearwardly and downwardly directed crank-arm C, the extremity of which is pivotally connected with the ends of a rod c, which extends forwardly and is bent transversely, affording a transverse central bar c',

which extends through a slot between the side walls of the press of the upper extension a^2 , as shown, Fig. 5. A rearwardly - curved upwardly - extending deflector - blade C' is rigidly engaged on said bar c' and, together with the presser-foot B when the feed-chamber is open, as shown in Fig. 3, affords the end walls of a hopper, the side walls of which are the extensions a^2 .

10 Rigidly secured on each end of the shaft b are the crank-arms B' , which extend forwardly and upwardly at approximately a right angle with the crank-arm C . Connecting-rods b^3 are pivotally connected to said crank-arms at their extremities and extend downwardly and pivotally engage crank-arms b^4 , rigidly secured on a shaft B^2 , journaled transversely of the press beneath the feed-chamber. Said shaft B^2 is provided 15 centrally with a rigidly-secured segment-shaped crank b^5 , which extends upwardly through the bottom of the press, as shown in Figs. 3 and 4, when the plunger is at its retracted limit of movement and the feed-chamber is fully opened.

As shown, powerful springs b^6 , shown as spiral springs, are engaged on each end of the shaft b , at one end engaging a fixed part on the frame of the press and at the other end a lug b^7 , carried on the hub of the crank-arm B' , and act normally to hold the presser-foot and crank-arm b^5 in their elevated position and the deflector C' retracted at the limit of its movement.

30 The plunger comprises a central solid head or beam D , rigidly secured between a lower and an upper flat plate d and d' , which fit the bottom and top, respectively, of the feed-chamber when the plunger is at the compressing limit of movement, as shown in Fig. 7. Brackets d^2 are rigidly secured on the inner faces of each of said plates d and d' , and pivoted at their ends on said brackets d^2 are slightly - incurved connecting-rods D' , each 35 of which extends rearwardly toward the head of the plunger and is provided on its extremity with a pivotally-supported blade D^2 , having a thin inwardly-directed edge which extends over the head of the plunger, as shown in Figs. 4, 6, and 7. Said blades are of a width to entirely close the space between the beam D of the plunger and the side walls a' and are of a length vertically to fit between the bottom and top of the press. Each of 50 said blades is engaged at the extremity of the connecting-rod D' by means of a suitable pivot-bearing, and a strong spring d^3 engages around said bearing and against the ends of the rods D' and at the other end 55 presses against said blade. The outer edge of the blade bears against the side walls of the feed-chamber and holds the inner edge of the blade in positive engagement with the head D at all times. As shown, also strong leaf-springs d^6 , though any suitable springs 60

will suffice, are engaged upon the head D and bear against each connecting-rod and act at all times to hold the same at its outward limit of movement.

The operation is as follows: The feeder 70 throws the hay, straw, excelsior, or other material to be compressed into the hopper when opened—that is to say, during the retracting movement of the plunger—filling the hopper to an extent sufficient to afford the 75 desired charge. During the compressing movement the blades D^2 bear against the sides of the press and afford a part of the plunger-head. As the plunger advances it 80 engages the lever-arm b^5 , which stands approximately vertically in the bottom of the feed-chamber, and forces the same rearwardly, as shown in Fig. 5, with the effect of drawing the crank-arm B' downwardly and the deflector C' inwardly and downwardly until the extremity of the presser-foot coincides with the upper end of the deflector and swings inwardly along the curved inner face of the same, pressing the hay or other material in the feed-chamber downwardly into the path of the plunger. The downward movement of the presser-foot continues until the same rests approximately in the plane of the top of the plunger, thus 85 affording a slight initial compression of the charge, which is completed as the plunger moves inwardly. The outer edges of the plates D^2 upon engagement with the inclined or converging walls a of the feed-chamber are forced inwardly against the compression of the spring d^6 , as shown in Figs. 6 and 7, thus 90 affording approximately a solid head as the charge nears the final compression limit and obviating any possibility of injury to said blades and connecting-rod, due to the force 95 of the compression. As the plunger is retracted the springs b^6 act immediately to elevate the presser-foot and detract the deflector as the plunger clears the lever - segment b^5 . The division-blocks E may be inserted, if desired, and while the plunger is 100 retracting. In this manner with each reciprocation of the plunger the hopper is opened and closed, and owing to the construction of the chamber and the expansible plunger a 105 charge of any desired size may be inserted with a certainty that the same will be compressed satisfactorily within the bale-chamber by the plunger, the area of which decreases as the pressure increases. 110

One very important advantage of this construction is that inasmuch as the presser-foot rests approximately upon the plunger during the latter portion of its compression movement none of the hay or material to be 115 pressed can be jammed between the plunger and the wall of the press, as frequently occurs with other presses. Furthermore, the downward sweep of the presser-foot against the curved side of the deflector C' serves to com- 120 125 130

press all the material into the feed-chamber into the proper position to be best engaged by the plunger.

Obviously, the plunger may be constructed otherwise than as herein shown to afford a broad bearing-surface during the initial compressing movement and a relatively small compressing-head during the final compressing movement, and also the means for compacting the charges in the feed-chamber preliminary to the compression may be varied. I therefore do not purpose limiting this application for patent otherwise than as necessitated by the prior art, as obviously many details of construction, including means for inserting division-blocks, may be varied without departing from the principles of my invention.

I claim as my invention—

1. A baling-press comprising a large feed-chamber converging to a compressing-chamber, a laterally-expansible plunger reciprocating in said feed-chamber, a presser-foot adapted to close the opening in the feed-chamber, a crank projecting through the bottom of the press into the path of said plunger and means connected therewith acting to operate said presser-foot.

2. A plunger for presses comprising a central member, laterally-movable members co-acting therewith and together affording a compressing-head, rods carrying said laterally-movable members, means acting to force said rods outwardly and means restricting the size of said head as the compression increases.

3. The combination with a press, of a large feed-chamber, converging to a bale-chamber, a plunger reciprocating therein and comprising an expansible head adapted to be decreased in size during the compressing movement, a presser-foot adapted to close the feed-chamber and a reciprocating plate adjacent said opening.

4. A press of the class described comprising a relatively broad hopper, converging end walls therefor opening into a bale-chamber, a compressing-head reciprocating in said chamber, rods pivoted at one end on said head and laterally-movable plates on their outer ends adapted to collapse inwardly during the compressing movement.

5. In a machine of the class described the combination in a press, of a reciprocating plunger therein, a feed-chamber comprising a broad hopper, a presser-foot pivoted on the press and acting to direct material into said hopper and a lever projecting through the bottom of the press in the path of the plunger acting to draw the presser-foot downwardly to afford initial compression of the material to be pressed.

6. A press comprising a feed-chamber, a broad hopper connected therewith by converging side walls, a longitudinally-reciprocating

deflector forming one end wall of said hopper, a plunger reciprocating in the feed-chamber and comprising relatively movable members adapted to collapse inwardly to fit the varying size of the feed-chamber during compression, and a presser-foot pivoted on the press and acting to close the hopper and force the contents downwardly during the compressing movement of the plunger.

7. In a machine of the class described, a plunger affording a varying compression-surface, the compressing area of said plunger decreasing laterally as the plunger approaches the limit of its compressing movement, a hopper comprising side walls and a longitudinally-reciprocating end wall and means adapted to close the hopper during the forward movement of the plunger.

8. In a machine of the class described a plunger comprising an expansible head, longitudinal rods pivotally supporting the expansible parts of the head, springs acting to normally hold said rods extended and converging side walls acting to reduce the size of the plunger as it approaches the limit of its movement.

9. In a machine of the class described the combination with a feed-chamber of a plunger therein, a presser-foot pivoted above the feed-chamber, a longitudinally-movable deflector and means for automatically operating said presser-foot and deflector.

10. In a machine of the class described the combination with a feed-chamber, of a reciprocating plunger therein, upwardly-extending side walls on said chamber, a swinging presser-foot pivoted at the rear thereof, a curved deflector at the opposite end of said walls, means operated by said plunger acting to simultaneously reciprocate the deflector and revolve the presser-foot.

11. In a machine of the class described the combination with an upwardly-opening feed-chamber, of a reciprocating plunger therein, side walls extending upwardly beyond the chamber, a shaft journaled at the rear end thereof, a presser-foot pivotally engaged on said shaft and adapted to close the opening in the feed-chamber, a curved deflector slidably engaged on the top of said chamber, a lever pivoted on the bottom of said chamber and extending into the path of the plunger and levers connecting the same with said deflector and presser-foot.

12. In a machine of the class described the combination with a feed-chamber having converging side walls and a reciprocating plunger therein comprising a central beam, upper and lower plates on said beam formed at their sides complementally, with the side walls, laterally-slidable plates at the inner end of said plunger, rods pivotally connected therewith and with said top and bottom plates, and means acting normally to hold said slidable plates retracted.

13. In a machine of the class described the combination in a bale-press of a reciprocating plunger, a hopper on said press, a pivoted plate forming one end of the hopper, a reciprocating plate forming the other end thereof and toggle-levers operated by the plunger acting to operate said reciprocating plate and force material into said press.

14. In a machine of the class described the combination with a compressing-chamber of a feed-chamber opening therein and provided with converging side walls, a plunger, rods pivoted on the side of the plunger, plates pivoted on the forward end of said rods and adapted to move transversely of the plunger and means engaging said rods adapted to normally hold said plates extended.

15. In a machine of the class described the combination with a compressing-chamber and feed-chamber of a plunger adapted to reciprocate therein, oppositely-movable plates on the forward end of the plunger, rods pivotally connected with the plunger and said plates and springs engaging between the plunger and rods adapted to hold said plates extended.

16. In a machine of the class described the combination with the compressing-chamber and feed-chamber of a plunger therein, rods pivoted at the sides of the plunger, transversely-movable plates pivoted at the forward end of said rods and overlapping the forward end of the plunger, springs adapted to hold said plates in close contact with the ends of the plunger and springs adapted to normally hold said plates at the outward limit of their movement.

17. A press comprising a feed-chamber, having converging side walls, a reciprocating plunger therein having recesses in the sides thereof, rods pivoted in said recesses, a plate pivoted at the outer end of each rod and adapted to move transversely of the plunger, springs acting to hold said plates in close engagement with the plunger and springs acting against said rods to normally hold said plates retracted.

18. A press comprising a feed-chamber, having converging side walls, a reciprocating plunger therein tapering toward its forward end, rods pivoted on said plunger and spring-controlled plates pivoted on said rods and adapted to move outwardly into alinement with the rear end of the plunger when the plunger is retracted.

19. A press comprising a frame, a shaft journaled therein, a presser-foot rigidly engaged on said shaft, a deflector slidably engaged on the frame, lever-arms connected therewith and with said shaft adapted to operate the same, a shaft journaled beneath the frame, a crank-arm thereon, means operatively connecting said shaft with the presser-foot shaft and a plunger adapted in its forward movement to engage said crank-arm and simultaneously depress the presser-foot and operate the deflector.

In testimony whereof I have hereunto subscribed my name in the presence of two subscribing witnesses.

MICHAEL BERT CORCORAN.
